CLAIM

The ornamental design for a lottery key chain, as shown.

DESCRIPTION

FIG. 1 is a front elevational view of a lottery key chain, showing my new design;

FIG. 2 is a front view thereof;

FIG. 3 is a rear view thereof;

FIG. 4 is a top view thereof;

FIG. 5 is a bottom view thereof;

FIG. 6 is a side view thereof; and,

FIG. 7 is an opposite side view thereof.

It being understood that the chain continues for an indeterminate length.
